UNITED STATES PATENT OFFICE.

CHARLES L. BUCKINGHAM, OF NEW YORK, N. Y.

PRINTING-TELEGRAPH.

SPECIFICATION forming part of Letters Patent No. 350,616, dated October 12, 1886.

Application filed March 6, 1886. Serial No. 194,209. (No model.)

To all whom it may concern:

Be it known that I, CHARLES L. BUCKINGHAM, of the city, county, and State of New York, a citizen of the United States of America, have made a new and useful Improvement in Printing-Telegraph Transmitters, of which the following is a specification.

My invention is applicable to that class of printing-telegraphs in which the step-by-step rotation of the type-wheels is controlled or effected by short electrical impulses, and in which the type-wheel is arrested during the operation of printing. In transmitters for this class of printing-telegraphs, a rotating pulsator is usually employed, which serves to direct short electrical impulses over the main line during its rotation, while for the purpose of prolonging an impulse the pulsator is arrested.

Where a single pulsator is employed in connection with many telegraph-circuits, the rotating apparatus is heavy, and, owing to its great momentum, is subject to constant injury and wear in the course of its operation, from the fact that it must be suddenly arrested many times a minute. Not only is there liability to derangement in this form of apparatus, owing to impact upon the arresting devices, where the apparatus is heavy, as is usually the case, but the inertia of the rotating parts is sufficient to greatly limit the speed of transmission.

The object of my invention is to avoid arresting the rotating pulsator during the operation of printing characters upon the receiving-instrument.

I will now explain my invention by reference to the accompanying drawings.

Figure 1 represents an arrangement of apparatus in which the pulsator is connected directly to the main line. Fig. 2 illustrates the pulsator as applied in a local circuit which controls a relay and main-line pole-changer. Fig. 3 illustrates the rotating pulsator with an additional device for rendering the first impulse transmitted, after the printing of a character, at least equal in length or duration to that of the normal impulse.

Referring particularly to Fig. 1 for convenience of illustration, H' and H" represent the coils of a polarized electro-magnet of a printing-instrument, controlling the step-by-step

rotation of a type-wheel, U, through the agency of pallet R and ratchet-wheel T.

J is a sluggish electro-magnet, which is also included in line L, for operating the press-lever P through armature V by the prolongation of one of the short impulses employed for controlling the rotation of the type-wheel.

The rotating pulsator-wheel is formed of two sections, M N, which are insulated from each other. Upon one of said sections conducting-spaces are arranged directly opposite the insulated-spaces of the other, and vice versa.

B' is a brush or spring connected with line L, whose broad end rests upon both sections of the rotating pulsator, and a b are springs or brushes respectively connected with said sections M N. Spring a is connected to the positive pole of battery A, while spring b is connected with the negative pole of battery B, and the opposite poles of said batteries are connected together and to earth at E'.

c is the shaft of the rotating pulsator-wheel, upon one end of which is a pinion, d, gearing with any suitable motor-train.

C is a circular series of conducting strips, commonly known as a "sunflower."

D is a sunflower-arm carrying a contact-spring at its free end, which, during the rotation of said arm, sweeps over the sunflower-strips.

E is an escapement-wheel, whose step-by-step rotation is controlled by an escapement-pallet, F, and armature I, while the latter is operated by the usual form of polarized electro-magnet, H' H", whose coils form a part of the main line L.

o is a contact-spring, which rests upon the periphery of the rotating shaft S, and is thereby electrically connected with arm D. The post upon which spring o is supported is connected by wire p, which includes the coils of electro-magnet G, and is thence connected to point 3 of the main line L.

G is a neutral electro-magnet having an armature, H, which is provided with a strong retracting-spring.

4 is a back electrical contact, to which line L is joined, and 5 is an insulated front stop.

There are as many insulated conducting-strips in the sunflower C as there are finger-keys upon the key-board of the transmitter

and characters upon a type-wheel, *k l m n* represent four such keys, having contacts *e f g h*, which latter are joined in sets to the main-line batteries. The contacts of alternate keys, 5 as *e g*, are connected together at point 1, and thence by wire *i* to the positive pole of battery A, while the other alternate set of key-contacts, as *f h*, are connected together at point 2, and thence by wire *j* to the negative pole of 10 battery B. Likewise one set of finger-keys, as *k m*, is connected to alternate sunflower-strips, while the other set, as *l n*, is connected to the second alternate series of the sunflower-strips. The necessity for this arrangement is 15 obvious from the fact that while a positive line-impulse always flows over the main line when the sunflower-arm comes in contact with the strip to which key *k* is connected, a negative impulse is on line when the arm comes in contact with a strip on either side of the one to 20 which key *k* is connected, and it is by this means that an impulse of either polarity may be prolonged to print, as occasion requires. It will now be seen that during the rotation of 25 shaft *c* short reversed electrical impulses are transmitted over the main line L through the coils of polarized electro-magnet of the sunflower device, and also through the coils of the type-wheel and the printing electro-magnet of 30 each receiving instrument. By depressing key *k* upon its contact *e* a circuit would be completed from battery A to the main line L, if the arm D were in contact with the sunflower-strip to which *k* is joined, through the coils of electro-magnet G. If, therefore, it were desired 35 to print the letter K, the key *k* would be depressed, and later on the rapidly-rotating arm D would come in contact with the sunflower-strip to which *k* is connected, and thereupon 40 electro-magnet G would attract the armature H from its back contact-stop, 4, thus breaking the main line L, and disconnecting the rotating pulsator from circuit. By this means the positive pole of battery A, which was before joined 45 to the main line through the rotating pulsator, would now be permanently connected to the main line at point 3 through wire *i*, key *k*, arm D, spring *o*, wire *p*, and electro-magnet G. Thus the impulse which was begun from 50 battery A through the rotating pulsator and armature H would be completed and prolonged for any desired period as soon as arm D had come in contact with the proper sunflower-strip, and as long thereafter as the key *k* remained depressed upon its contact *e*. The prolonged impulse thus transmitted arrests the escapement-wheel E of the sunflower device, 55 as well as the escapement-wheel T of the receiving-instrument. Upon releasing the key *k* from its contact *e*, the circuit through electro-magnet G is broken, and the armature-lever H is returned to its back contact, 4, rejoining the pulsator with the main line, and short electrical impulses are again transmitted 60 from the pulsator over the main line and through the magnets H' H" of the sunflower

device, as well as through those of the receiving-instruments. The arm D of the sunflower device must be rotated in unison with the type-wheels of the receiving-instruments, and, like 7c the latter, must be provided with a unison apparatus. If alternate sunflower-strips are connected to one battery, and the other set of alternate strips is connected to the other battery through the transmitting-keys, as shown, 75 it is obvious that unison need not be maintained between the rotating pulsator-wheel and the type-wheels of the receiving-instruments, as is necessary where the pulsator is stopped at the printing of each character, but 80 that any number of impulses may be transmitted from the pulsator over the main line when the pulsator may be disconnected from line and continue to rotate while the type-wheels of the receiving-instruments are held 85 stationary.

It will be observed that with the device shown in Fig. 1, after the printing of a character the pulsator-wheel might be reconnected with the main line, while the end of brush B' 90 was near the middle or end of a conducting-section of the pulsator. If the circuit through armature H were completed under these conditions, the first impulse transmitted after the printing of a character would be of less than 95 normal duration. In printing-instruments of this character, however, it is necessary that the electrical impulses transmitted from the pulsator shall be of substantially equal duration, for the reason that if the armatures of 100 the escapement-magnets of the different receiving-instruments on the line were differently adjusted, as is unavoidably the case, the short impulse might be sufficient to operate the escapement of some instruments and not of others. Thus the instruments on a circuit would be thrown out of unison.

In order that the first impulse transmitted after the printing of a character may not be less than of normal duration, I employ a device (shown in Fig. 3) in which the spring B' is mounted upon an arm, *r*, having an armature, *x*, a retracting-spring, *y*, and a pawl, *t*, under the free end of which rotate the teeth of the ratchet-wheel *u*. The arm *r* is loosely 115 mounted upon shaft *c* of the rotating pulsator, while the ratchet-wheel *u* is rigidly affixed to said shaft and rotates therewith. The ratchet-teeth of wheel *u* are spaced to correspond with the insulating and conducting spaces of the 120 pulsator-wheel, and in such manner that if the arm *r* were drawn backward by the retracting-spring *y*, after the end of spring B' had once come in contact with a conducting portion of one section of the pulsator-wheel, as H, 125 said spring could not be thrown so far forward as to pass beyond the conducting-space of section N and pass to the succeeding conducting-space of section M. It will be seen from Fig. 3 that upon depressing key *k*, after the arrival 130 of brush D to the corresponding sunflower-strip, armature *x* will be attracted by electro-

magnet W, whose coils form a part of the same circuit as those of electro-magnet G, bringing armature-lever *r* in contact with front stop, *z*. Upon releasing key *k* spring *y* would retract 5 armature-lever *r*, carrying the contact-spring B' forward in direction of rotation of the rotating pulsator. The spring *y* is of such tension as to move the free end of conducting-spring B' more rapidly than the periphery of the pulsator-wheel rotates, and were it not for the ratchet-wheel *u*, after the point of spring B' had come 10 in contact with a conducting portion of the pulsator, it might be thrown forward in advance of said conducting portion of one section of the pulsator into contact with the conducting 15 portion of the other section. By means of the ratchet-wheel *u* and pawl *t*, however rapidly the end of spring B' may be moved over the periphery of the pulsator-wheel, it cannot 20 be moved beyond the forward end of the conducting portion with which it first comes in contact. By this means the first impulse transmitted to line after the printing of a character will, in any event, be equal in duration to that 25 of the normal impulse, and may be somewhat longer.

In Fig. 2 I have shown an arrangement in which the pulsator and the electro-magnet controlling the sunflower are placed in a local circuit, which also includes polarized electro-magnets Z'Z", for operating the main-line pole-changer P C, which at each movement reverses the battery M B upon the main line L. This arrangement is obviously a mere modification 35 of that shown in Figs. 1 and 3.

I do not wish to limit my invention to telegraph systems in which the rotation of the type-wheel is controlled by current-reversals, nor in which the rotation of the type-wheels 40 is effected by clock-work and a releasing-escapement, nor in which the type-wheel magnets and the printing-magnets are included in a single circuit, as it is equally applicable to systems in which the rotation of the type-wheels is effected by electrical impulses of one 45 polarity, and in which the rotation of the type-wheel is effected by an impelling electro-magnet, and in which a main line, including the type-wheel magnets, and an independent main 50 line, including the printing-magnets, are employed.

What I claim, and desire to secure by Letters Patent, is—

1. In a printing-telegraph system, the combination of a constantly-rotating pulsator, a main line including the pulsator, type-wheel magnets, and printing-magnets, and a transmitter for sending a continuous current over the main line independent of the constantly-rotating pulsator, for the purpose of holding the type-wheels at rest for any desired period during the continued rotation of said pulsator. 60

2. In a printing-telegraph system, the combination of a constantly-rotating pulsator, a circuit including said pulsator, the type-wheel and printing electro-magnets, and a battery or

batteries, a normally-open branch around the pulsator for joining the battery or batteries with the circuit, a sunflower arrangement whose arm may be arrested, and transmitting-keys, the whole being so arranged that a continuous current may be transmitted to line and the type-wheels arrested during any desired period while the constantly-rotating pulsator continues in motion. 75

3. In a printing-telegraph system, the combination of a constantly-rotating pulsator, a battery or batteries, a series of transmitting-keys, a sunflower arrangement, an electro-magnet for effecting or controlling the rotation 80 of the sunflower-arm, and branch circuits around the pulsator, substantially as described, which are normally open at the transmitting-keys and sunflower-strips, as and for the purpose described. 85

4. In a printing-telegraph system, a sunflower device whose arm rotates in unison with the type-wheel of the receiving-instrument, a series of branches connecting the sunflower-strips with the transmitting-keys, a conductor 90 or conductors joining the anvils of the transmitting-keys with the battery or batteries connected to the constantly-rotating pulsator, and an electro-magnetic switch for breaking the pulsator-circuit when a circuit from said battery or batteries is completed through a transmitting-key and a sunflower-connection, substantially as described. 95

5. In a transmitter for a printing-telegraph system, a branch circuit which is normally open 100 at the transmitting-keys and at the sunflower device, and which is closed upon depressing a transmitting-key when the sunflower-arm is in contact with a corresponding strip, an electro-magnet in said normally-open 105 branch circuit, a constantly-rotating pulsator, a switch controlled by the electro-magnet in said normally-open branch circuit for breaking and closing the pulsator-circuit, an electro-magnet for controlling the rotation of the 110 sunflower-arm, and an electro-magnet or electro-magnets for controlling the operation of the receiving-instruments, substantially as described. 115

6. In a printing-telegraph system, a constantly-rotating pulsator, a transmitting-battery, a branch circuit or circuits and transmitting keys, and a sunflower device or its equivalent for constantly connecting the transmitting-battery in circuit upon the depression 120 of transmitting-keys. 125

7. In a printing-telegraph transmitter, a constantly-rotating pulsator, a movable contact-spring, B', and means, substantially as described, whereby said spring may move in the direction of rotation of the pulsator upon directing impulses from said pulsator over the main line, as and for the purpose described. 125
